UNITED STATES PATENT OFFICE

EDWARD C. WALTER, OF HARRISBURG, PENNSYLVANIA, ASSIGNOR TO ELLIOTT-FISHER COMPANY, OF NEW YORK, N. Y., A CORPORATION OF DELAWARE

CARD INDEX

Application filed March 13, 1925. Serial No. 15,404.

This invention relates to card index systems of the type in which card holders, carrying index cards, are nested in a tray in which they are hinged in such a way that while great economy of space may be secured with only a title margin of the cards exposed, any card may be fully exposed for the entry or reception of data by swinging the adjacent card, or cards, away from the one to be inspected.

The object of the present invention is to produce a system of this character, possessing all of the usual advantages but capable, in addition, of presenting each card when desired in an elevated writing plane where it may be held in a substantially horizontal position on a posting board or platen, to facilitate the entry thereon of typewritten or other postings.

20 In the accompanying drawings:

Figure 1 is a sectional view of my index device, arranged for use in connection with a flat platen typewriter.

Figure 2 is a plan view of the same.

25 Figure 3 is a longitudinal section through the subject matter of Figure 2.

Figure 4 is a perspective view of one of the index members.

Figure 5 is a similar view showing the 30 manner in which the double hinge is utilized to present the record portion of the device in a posting plane, different from the storage plane, and

Figures 6 and 7 are detailed views of the 35 platen and tray supporting brackets.

Referring first to the index system, 1 indicates a tray of usual form, having at opposite sides of its bottom longitudinal guides or ways 2, for the retaining tabs 3 of index devices 4. These index devices include a card-holding portion 5, a retaining portion 6, and an intermediate hinged connection portion 7. The index portion 5 may carry the record directly, but usually serves for the retention of an index card 8, held in place by any suitable means, as, for instance, celluloid or any other margin strips 9, extending across the free edge of the holder, and corner strips 10, produced by forming

40 diagonal slits 11 in the holder. The retain-

ing tabs 3 may be formed integral with the retaining portion 6 of the index device, but are preferably formed by the extended ends of a separate retaining strip 12, secured to the retaining portion 6 by staples or other suitable securing means 13. Similar staples 14 may be employed to secure the margin strips 9 to the holder and, if desired, certain or all of them may pass through the card.

The intermediate or hinged connecting portion 7 of the index device is connected along its opposite edges by hinges 15 and 16, with the record portion 5 and the retaining portion 6 of the device. As these portions or elements of the record device are preferably integral, being formed from a single piece of cardboard or other similar material, the hinges in the illustrated embodiment of the invention are produced by forming weakening lines in the material, as, for instance, rows of apertures 17, so that while the individual record devices ordinarily lie flat in a slightly inclined storage plane, the lower hinge 16 will permit the device to be thrown forward or back in the tray in the usual manner, or allow the intermediate portion 7 to stand vertically with the record portion 5 swung on the hinge 15 to a horizontal position, in a somewhat elevated posting plane. The several positions which the device is capable of assuming in the tray are clearly shown in Figure 3, wherein some of the record devices lie in their normal storage position, others are thrown back and one is in position for posting. When in the posting 80 position the record portion of the device is intended to be supported by a posting board or platen 18, which may be supported by the tray and removable from the posting position to facilitate the handling of the record devices in the tray, or as in the illustrated showing it may be the platen of a typewriter.

While the structure thus far described constitutes a complete embodiment of the invention in certain aspects thereof, I have devised certain novel structures designed to facilitate the posting of these card index records by a flat platen typewriter.

45 In Figure 1 is diagrammatically shown the 90

ordinary Elliott-Fisher typewriter of commerce 19, the printing head of which is transversely movable for letter spacing on a line-space frame 20, movable longitudinally of a 5 platen frame 21, to line space the matter printed.

For the purpose of the present disclosure it is unnecessary to illustrate or describe the manner in which the line-space frame 20 is 10 constructed and operated. Suffice it to say that it is equipped with supporting rolls as shown in dotted lines at 22, and with line-spacing mechanism permitting it to be moved rearwardly to clear the platen as is well 15 understood in this art.

Within the platen frame 21 are mounted brackets 23 and 24, arranged in pairs at opposite sides thereof. Mounted to swing on a shaft or pintle 23^a, extended between the 20 brackets 23, is a flat platen 25, preferably having a hard rubber or other facing 26 as usual, and supported at its free side or end by rubber or other suitable cushions 27, carried by the brackets 24. The platen 18, when 25 in its depressed position, overlies the tray 1 which is supported by rolls 28 mounted on shafts 29, the ends of which are extended through ears 30 formed on the brackets 23 and 24. For the purpose of accurately guiding the tray 1 in its movement on its supporting rolls 28, guide rollers 31 engage opposite sides of the tray and are carried by transverse frame members 32. It will now 30 be seen that when the index devices are arranged in the tray 1, as shown in Figure 3, the latter may be placed in the machine for the posting of the records. The platen 26 being swung up on its pintle 23^a, the line-space frame 20, of course, having first been 35 moved to clear the platen, the record device which it is desired to post, is swung upward from the tray with the hinge 16 as an axis. The platen is then swung down to its horizontal position and the record portion 5 of the index device is swung down upon the 40 platen from the hinge 15 as an axis. The parts will now occupy the position shown in Figure 3 and the printing mechanism may now be moved to a position over the platen 45 for the posting of the record, either on the card 8 or on the record portion of the device itself.

It should be understood in this connection, that in using the term, index device, I intend to cover the structures shown in Figures 3 and 4, either with or without the card. A card, when in position, becomes a part of the index device, but it is obvious that, but for the consideration of economy, the removable writing surface or card might be eliminated. Also, it is obvious that while my index system is shown in use in connection with the flat platen of a typewriting machine, it is immaterial, in certain aspects of the invention, how the record is posted. Ob-

viously, the platen 18 may be considered merely as a posting board and instead of having independent supports, might, if desired, be supported by the tray. It is preferable, however, in any case to extend the posting board or platen, beyond the sides of the tray to form an arm rest. 70

What I claim is:—

1. In a machine of the character described, 75 the combination with a frame, and supporting and guiding rolls, of an open top tray removably supported by said rolls and movable lengthwise thereon, a series of index cards stored in the tray and overlapping lengthwise thereof, means for securing one edge portion of the cards adjacent the bottom of the tray, the opposite edge portions of the cards being movable to a position above the tray, and a platen mounted above the tray and extending transversely thereof to receive the movable edge portion of a card, said platen being hinged to be swung from over the tray to facilitate removal of the latter from said guiding rolls. 80

2. The combination with a frame and supporting and guiding rolls thereon, of an open top tray removably supported by said rolls and lengthwise movable thereon, a series of index cards adapted to be stored in the tray and having an edge portion secured adjacent the bottom of the tray, each card being hinged near its secured edge portion and including a section movable to a horizontal plane above the side walls of the tray, and a flat platen overlying the tray to receive said section of the card, the platen being hinged to the frame for movement to or from its overlying position. 95

3. A card index, including a tray, a series 100 of overlapping cards mounted in the tray with their edges exposed to facilitate selection, each of said cards including three connected sections, to-wit, a posting section on which the record is to be posted, a retaining section engaging the tray to retain the card therein and an intermediate swinging section oppositely hinged to the retaining section and to the posting section, whereby the card may lie flat in the tray, or be lifted out 105 of the tray for posting with the intermediate card section swung to a vertical position and the posting section occupying an elevated horizontal position, and means for supporting the posting section during the posting operation. 110

4. In a card index posting machine, a support, an open top tray and an overlying flat platen mounted on the support in individual planes, respectively, and a series of overlapping cards in the tray, each including, a stationary marginal retaining section, a posting section, and spaced oppositely acting 115 hinges adjacent the retaining section whereby the posting portion of the card may be 120

125 130

raised from the tray to be positioned upon the platen and used for posting operations.

5. An index card for use with a posting tray, said card including at least three sections one of which is provided with devices for securing it adjacent the bottom of the tray, said sections being hinged together to fold one over another in the tray or to locate a section of the card above the tray in horizontal position for the writing of a posting thereon.

6. In a card index posting machine, a support, an open top tray and a superposed flat platen mounted on the support and one movable in a plane parallel to the plane of the other, a series of overlapping cards each having a relatively narrow section hinged adjacent the bottom of the tray to swing from a horizontal to a vertical position, and a relatively wide posting section hinged to the swinging section to assume a horizontal position on the platen when said swinging section is swung to a vertical position, said swinging section corresponding in width substantially to the distance between the bottom of the tray and the printing plane of the platen.

7. A card index, including a series of overlapping cards having respectively, a posting section on which the record is adapted to be posted, a narrow retaining section, and an intermediate section oppositely hinged to the posting and retaining sections of the card whereby the card may assume a flat horizontal position or a position in which the posting and retaining sections will extend in opposite directions from the intermediate section and in parallel planes, and a tray adapted to hold said retaining section of the cards.

40 8. A card for card indexes including, a relatively large section on which the record is adapted to be posted, a narrow retaining section extending beyond the side edges of the posting section, and an intermediate section oppositely hinged to the posting and retaining sections whereby the card may assume a flat horizontal position or a position in which the posting and retaining sections will extend in opposite directions from the intermediate section, in right-angular relation thereto and in parallel planes.

In testimony whereof I hereunto affix my signature.

EDWARD C. WALTER.
